UNITED STATES PATENT OFFICE.

ROBERT E. PIERCE, OF ST. LOUIS, AND EDWIN A. REED, OF MAPLEWOOD, MISSOURI.

TAKE-UP MECHANISM.

1,158,840.

Specification of Letters Patent.

Patented Nov. 2, 1915.

Application filed April 16, 1914. Serial No. 832,287.

To all whom it may concern:

Be it known that we, ROBERT E. PIERCE and EDWIN A. REED, citizens of the United States, residing in St. Louis and Maplewood, 5 St. Louis county, Missouri, respectively, have invented a certain new and useful Improvement in Take-Up Mechanisms, of which the following is a full, clear, and exact description, such as will enable others skilled 10 in the art to which it appertains to make and use the same.

This invention relates to take-up mechanisms for sewing machines, and has for its main object to provide a take-up mechanism 15 which is so designed that it will not "overthrow" or move beyond its normal limit of movement when the machine is running at a high speed.

Another object is to provide a take-up 20 mechanism which acts on the thread in such a manner that there is little tendency for the thread to break when said mechanism is taking up the slack in the thread.

Another object is to provide an accessible 25 take-up mechanism of simple construction for sewing machines which is so designed that the thread can be arranged in operative position in same easily; and still another object is to provide a take-up mechanism 30 that comprises a substantially drum-shaped member around which the thread passes.

Other objects and desirable features of 35 our invention will be hereinafter pointed out.

Figure 1 of the drawings is a side elevational view of a take-up mechanism constructed in accordance with our invention, the housing or casing that protects said mechanism being broken away. Fig. 2 is a 40 similar view showing said mechanism at the end of its forward stroke after it has taken up the slack in the thread. Fig. 3 is a vertical sectional view taken on approximately the line 3—3 of Fig. 1. Fig. 4 is a view 45 similar to Fig. 2, but with the parts adjusted differently; and Fig. 5 is a sectional view on the line 3^a—3^a of Fig. 4.

Referring to the drawings which illustrate 50 the preferred form of our invention, a designates a thread that leads from a source of supply to the work on which the machine is operating and A designates a take-up member that moves intermittently when the machine is in operation so as to take up 55 the slack in the thread and draw it taut. The take-up member A is in the form of a

drum and oscillates back and forth, preferably about a horizontal axis. It is preferably provided with two thread-engaging devices 1 and 1^a that are located on opposite sides 60 of the axis of movement of the member A. In the embodiment of our invention herein shown the thread-engaging devices 1 and 1^a are set in the edge of the drum A and are located on opposite sides of a stationary thread guide consisting of two rollers 2 and 2^a arranged on opposite sides of the thread and spaced a slight distance away from each other on opposite sides of the axis of movement of the drum A, as 65 shown in Figs. 1 and 2. The devices 1 and 1^a on the drum A lie on opposite sides of the thread and they are so arranged with relation to the rollers 2 and 2^a that constitute said stationary thread guide that said rollers 70 2 and 2^a will exert pressure on the thread in opposite directions to the direction which the devices 1 and 1^a exert pressure on the thread when the take-up member A moves 75 forwardly. As soon as said take-up member starts to move forwardly from the positions shown in Fig. 1 a thread-locking device, 80 which will be hereinafter described, clamps the thread at a point intermediate the take-up mechanism and the source of supply, and consequently, the slack in the thread will be taken up by the time the member A reaches the position shown in Fig. 2. In 85 other words, when the member A moves forwardly, the device 1 on said member travels upwardly past the stationary guide roller 2, and the device 1^a on said member travels downwardly past the guide roller 2^a, thus winding the thread in a zig-zag manner 90 between said devices and rollers and taking up the slack in the thread. The devices 1 and 1^a preferably consist of rollers that are rotatably mounted on the drum A, so that the thread will draw through said devices 95 easily and said rollers and also the rollers 2 and 2^a are preferably grooved so as to prevent the thread from slipping off same. The front edge portion of the drum A extends 100 forwardly slightly beyond the rollers 1 and 1^a, as shown in Fig. 3, and the outer surface 105 of the drum can be provided with a groove, as shown in Fig. 5, for receiving the thread or a flange can be formed on the front edge of the drum so as to prevent the thread from slipping off the drum when the mechanism 110 is so adjusted that the thread lays on the drum A or extends around same during the

operation of taking up the slack in the thread.

It is immaterial, so far as our broad idea is concerned, how the take-up drum is mounted, but we prefer to mount said member loosely on a stationary stud 3 that is provided at its outer end with an enlarged head or cap plate 4 which laps over a vertically-disposed wall at the inner end of the drum 10 and thus holds it in operative position. Said stud 3 is secured to the head of the machine by means of screws or other suitable fastening devices 5, and the rollers 2 and 2^a that constitute the stationary thread guide are 15 rotatably mounted on studs 6 that are connected to the cap plate of the stud 3.

Various means may be employed for actuating the take-up drum A, the means herein shown consisting of a rock arm 7 provided with a toothed segment 8 that meshes with a circular rack or gear 9 that is secured to the rear side of the vertical wall at the end of the drum A, and a bell crank lever 10 for operating the rock arm 7. Said bell 25 crank lever is pivotally connected at 11 to a stationary part of the head of the machine, and one arm of said lever is provided with a laterally projecting stud or roller 12 that cooperates with a cam 13, which rotates 30 continuously when the machine is in operation. The other arm of the lever 10 is provided with an adjustable stud or block 14 that enters an elongated slot 15 in the rock lever 7, said stud being adjustably mounted 35 in a slot 16 in the lever 10 that is arranged at an angle to the elongated slot 15 in the rock arm 7.

The thread-locking device previously mentioned is of novel construction and consists of two coöperating members 17 and 18, through which the thread travels, the member 17 being stationary and the member 18 movable. The movable member 18 is actuated by a lever 19 pivotally connected 45 intermediate its ends to a stationary part of the head of the machine and having its upper end pivotally connected at 20 to the movable thread-clamping member 18. A spring 21 that is connected to the lower end 50 of the lever 19 and to a bracket 22 on the head of the machine tends to force the movable thread-clamping member 18 toward its coöperating stationary member 17, and means are provided for moving the lever 55 19 in the opposite direction to the direction which the spring 22 moves it and holding it in such a position that the member 18 will not clamp the thread when the take-up member is idle or in a position shown in 60 Fig. 1. The means herein shown for this purpose consists of an adjustable stop 23 on the take-up drum A that bears against the lower end of the lever 19 when said take-up drum is at its position of rest shown in 65 Fig. 1, said adjustable stop being carried

by an arm 24 that projects radially from the periphery of the drum A. The actuating lever 19 of the thread-locking device is provided adjacent its lower end with a guide 25 through which the thread passes, 70 and the coöperating thread-engaging members 17 and 18 are provided with sinuous shaped thread-gripping surfaces so as to hold the thread α securely without liability of cutting the thread. The member 17 preferably consists of a stationary block on the head of the machine provided at its upper and lower ends with laterally projecting guides or bifurcated jaws 17^a, and the movable member 18 slides between said 80 jaws and is provided at its upper and lower ends with ribs 18^a that project into the slots in said jaws so as to hold the members 17 and 18 in alinement with each other. In view of the fact that the adjustable stop 85 23 on the take-up drum A is arranged some distance from the axis of movement of said drum A, said stop will release the lever 19 of the thread-locking device at practically the same instant the drum A starts to move 90 and before said drum starts to take up the slack in the thread, consequently, there is no possibility of the thread being drawn from the source of supply when the take-up mechanism becomes operative. 95

Another desirable feature of a thread-locking device of the construction above described is that the thread can be arranged in operative position between the members 17 and 18 simply by withdrawing the member 18 from the member 17 and then slipping the thread sidewise into the jaws 17^a in the member 17, the member 18 being thereafter slipped back into position so as to clamp the thread when the take-up member starts to 105 move. The thread extends in practically a straight line from the thread-locking device to the work when the take-up mechanism is idle and said thread-locking device and take-up mechanism are so designed that there is no liability of cutting the thread or 110 breaking the thread when the take-up mechanism is operating. By changing the position of the adjustable stop 23, the action of the thread-locking device can be accurately regulated, and by changing the position of the block or stud 14 in the bell crank lever 10 the throw of the rock arm 7 can be varied so as to change the degree of 115 movement of the take-up member A. For 120 example, by shifting the stud 14 to the opposite end of the slot 15 in the rock lever 7, as shown in Fig. 4, a greater degree of movement will be imparted to the take-up drum A. When the mechanism is adjusted 125 in this manner the thread will extend farther around the drum, and consequently, the convexed surface of the drum will exert pressure on the thread and thus take up the 130 thread. While we prefer to design the

take-up mechanism in such a manner that the thread extends only part-way around the drum A during the operation of taking up the slack in the thread, we wish it to be understood that our invention is not limited to such a design, for our invention broadly stated consists in a take-up mechanism composed of a drum or drum-shaped member through which the thread extends at approximately right angles to the axis of movement of the drum and means for oscillating or rotating said member intermittently. Furthermore, while we prefer to equip the mechanism with a stationary thread-guide arranged adjacent the axis of movement of the drum, this is not essential to the successful operation of our improved mechanism, for in the simplest form of our invention the thread would merely enter one side of the drum and extend transversely across same to the opposite side of the drum.

The take-up mechanism and the thread-locking device are arranged in such a position on the head of the machine that they can be gotten at easily, either for the purpose of adjustment, or when the thread is being arranged in operative position, and said parts are preferably inclosed by a movable housing 26 so as to keep wax or any other coating on the thread in a more or less plastic condition.

In our improved take-up mechanism there is no tendency for the take-up member to over-throw or move beyond its normal limit of movement when the machine is run at a high speed, owing to the fact that said member oscillates back and forth, preferably around a stationary thread guide which engages the thread intermediate two devices 40 on the take-up member which move the thread in opposite directions with relation to the stationary center guide, consequently, it is possible to run a sewing machine equipped with our improved take-up mechanism at a high speed without liability of breaking the thread. Nor is there any tendency for the thread to catch on or become looped improperly around any parts of the take-up member, in case the thread becomes slack when the take-up member is moving back to its starting position, owing to the fact that the convexed surface of the drum over which the thread extends prevents the thread from doubling up or assuming such a position that it lies in the path of the thread-engaging devices on the drum. In other words, the portions of the drum that lie between the two thread-engaging devices 1 and 1^a constitute convexed shields 55 that prevent the thread from becoming looped around said devices. The thread can be slipped sidewise into the take-up mechanism without going to the trouble of inserting the free end of the thread through a number of eyes or orifices in guides, and the

cooperating thread-clamping members of the thread-locking device are so designed that the thread can be slipped sidewise into same. Suitable means are provided for varying the throw of the take-up member 70 and for accurately adjusting the thread-locking device, and as said locking device is controlled directly by the take-up mechanism and is so designed that it locks the thread at practically the same instant the 75 take-up member starts to move forwardly, there is little liability of the thread being pulled from the source of supply during the operation of taking up the slack in the thread. The thread has practically a 80 straight pull through the take-up mechanism, and thread-locking device when the take-up mechanism is idle and said parts are so arranged on the head of the machine that they can be gotten at easily. Furthermore, 85 said mechanism and device are protected by a movable housing or casing which retains sufficient heat around said parts to keep the wax on the thread in a plastic or semi-plastic state.

Having thus described our invention, what we claim is:

1. A take-up mechanism for sewing machines, comprising an oscillating take-up member provided with a plurality of thread-engaging portions that move or exert pressure on the thread in opposite directions, said take-up member having convexed portion arranged intermediate said thread-engaging portions over which the thread 95 passes when said member is in a certain position.

2. A take-up mechanism for sewing machines comprising a take-up member having a substantially cylindrical-shaped portion provided at oppositely-disposed points with openings through which the thread extends transversely of said member, and means for moving said member in a circular path so as to cause the thread to tend 100 to wrap around the curved outer surface of same.

3. A take-up mechanism for sewing machines comprising a circular moving take-up member having an approximately ring-shaped portion provided with substantially oppositely-disposed openings through which the thread extends transversely of said member, and a stationary guide at the axis of movement of said member through which 110 the thread passes.

4. A take-up mechanism for sewing machines comprising an oscillating take-up member having a substantially cylindrical-shaped portion equipped with thread-engaging devices that are located on opposite sides of the thread, and means arranged intermediate said devices which exerts pressure on the thread in opposite directions to said devices when the take-up member operates. 125

5. A take-up mechanism for sewing machines, comprising a circular moving take-up member provided with a substantially ring-shaped portion equipped with a pair of spaced rollers that are arranged on opposite sides of the thread, and a plurality of stationary rollers arranged intermediate the rollers on said member adjacent the axis of movement of said member so as to form a 10 guide through which the thread passes.

6. A take-up mechanism for sewing machines, comprising an oscillating take-up member provided with a circular flange, a stationary stud on which said member is 15 mounted, thread-engaging devices on said member arranged adjacent said flange on opposite sides of the thread, and a stationary thread guide carried by said stud.

7. A take-up mechanism for sewing machines, comprising a circular moving take-up member, a stationary stud on which said member is mounted, thread-engaging devices on said member arranged on opposite sides of the thread, segmental-shaped, convexed portions on said member arranged intermediate said thread-engaging devices and a stationary thread guide carried by said stud and consisting of spaced rollers that prevent the thread from moving bodily 20 when it is engaged by the thread-engaging devices and convexed portions on said member.

8. A take-up mechanism for sewing machines, comprising a circular moving drum

through which the thread passes transversely, means for actuating said member so as to cause the thread to lay upon the curved surface of same, and means whereby the degree of movement imparted to said member may be varied.

9. In a sewing machine, a thread-locking device, a take-up mechanism comprising an oscillating drum-shaped member through which the thread extends transversely, and adjustable means on said member located some distance from the axis of movement of same for controlling said locking device.

10. In a sewing machine, a thread-locking device comprising a movable clamping member, a spring-controlled lever for actuating said member, a guide on said lever through which the thread passes, an oscillating take-up member provided with a substantially-cylindrical-shaped portion through which the thread extends transversely and an adjustable means on said member that coöperates with said lever to hold said movable clamping member in an inoperative position when said take-up member is at rest.

In testimony whereof we hereunto affix our signatures in the presence of two witnesses, this 11th day of April, 1914.

ROBERT E. PIERCE.
EDWIN A. REED.
